MOTION PICTURE APPARATUS

Arthur Allen Andrews, Tiptree, England

Application April 25, 1934, Serial No. 722,330
In Great Britain March 28, 1933

1 Claim. (Cl. 88—18.4)

This invention relates to kinematographic apparatus for taking and/or projecting motion pictures, and concerns mechanism for feeding the film and for retaining same stationary between successive film-feeding operations, that is to say, during those periods when the firm-feeding means is disengaged from the film, so that the film is correctly placed for re-engagement of the feeding means to impart further advancing motion to the film.

An object of the invention is to provide an efficient mechanism for achieving these purposes, which is extremely simple in construction, capable of cheap manufacture and foolproof in operation.

A further object of the invention is to provide a mechanism in which the claws of a film-feeding device are maintained perpendicular to the film, thereby ensuring accurate engagement and avoiding tearing of the film.

The accompanying drawing forming a part of this specification illustrates an apparatus of practical form in accordance with the invention, and in the drawing:—

Figure 1 is a side view of the apparatus with cover removed.

Figure 2 is a front end view, the casing being shown in section; and,

Figure 3 is a fragmentary vertical section illustrating the working of the apparatus.

The apparatus shown in the drawing comprises a casing 1, which is divided by a vertically disposed partition 2, into two compartments 3 and 4 respectively, and on said partition 2, and in the compartment 3 there is mounted the lens-carrying member 5.

Adjacent the rear end of the lens-carrying member 5 there is fixedly mounted a vertically disposed plate 6 which is provided with a right-angled extension cheek 7 abutting the partition 2, and in said plate 6 is formed the gate or gap 8. The gate or gap 8 is adapted to be covered and uncovered by means of the shutter 9 which is vertically slidable in and between channel guides 10 on the plate 6 aforesaid.

The shutter 9 fixedly carries a horizontally disposed pin 11 on which is disposed in front of the gate plate 6 a slidably mounted sleeve 12 which is pivotally and eccentrically mounted on a disc 13 located in the compartment 4 and positioned above the lens-carrying member 5. The spindle of the disc 13 is rotatable in and extends through the partition 2 into the compartment 3 and is fitted with a pinion 14.

The pinion 14 meshes with a spur wheel 15

which meshes with a pinion 16 on the end of a spindle which is rotatable in and extends through the partition 2 into the compartment 4 and below the lens-carrying member 5, said spindle having mounted thereon a disc 17 on which is pivotally and eccentrically mounted the double-pronged claw 18.

The channel guides 10 formed on the plate are extended down below the gate 8 so as to serve for the slidable reception therein of a plate 19 furnished with a fixed laterally projecting pin 20 which is slidably engaged in a bore formed in the claw member 18, said plate 19 being apertured to afford passage for the film-engaging prongs 21. The pin 20 serves as a guide to maintain the claw 18 in a position on which the prongs 21 are perpendicular to the film track during the complete cycle of operations of the claw.

The claw 18 has pivotally attached to it a tail member 22 which is slidably engaged in a block 23, said block 23 being pivotally mounted on a screwed pin 24 which engages into a boss 25 provided on the partition 2.

The block has pivotally connected to it the film-retaining pin 26, the pointed free end of which engages in a pin hole 27 formed in the lower part of the gate plate 6, in which, and opposite the pronged claw 18, is formed a vertically disposed slot 28 for the reception and movement therein of the prongs 21 of the claw 18.

On the extension cheek 7 of the gate plate 6 there is hinged, so as to swing about a vertical axis, a vertically disposed back plate 29 carrying a presser plate 30 in which, and opposite to the pin hole 27 of said gate plate 6, is formed an aperture 31 into which the end of the film-retaining pin 26 is adapted to enter. The back plate 29 is held closed by a slidable clip (not shown).

The presser plate 30 is controlled by light springs 32 and acts as a presser to the film 33 which is led from the top spool 34 down to and over a guide post 35 on the extension 7, then down and past the gate 8 to and down between the gate plate 6 and presser plate 30, then under the lower end of said presser plate 30 to the bottom spool 36, the latter being mounted on a rotatable spindle 37.

The rotatable spindle 37 extends into the compartment 3 of the casing 1, and is fitted with a pulley or like wheel 38 which is coupled by an endless coil spring band 39, or equivalent, to a pulley or like wheel 40 mounted on the spindle of the spur wheel 15, said spur wheel 15 being fitted as shown in Figure 2, with a cranked handle 41.

Assuming the movable parts to be in the position shown in Figures 1 and 2, i. e. exposure position with shutter 9 raised and claw 18 fully retracted, and film-retaining pin 25 just on the point of disengagement from the film 33, then, on turning the handle 41, rotation is imparted through the gears 15, 14 and 16, to the discs 13 and 17 simultaneously, with the result that the shutter 9, through the combined movements of said disc 13, and its sleeve 12 on the pin 11 of the shutter 9, is caused to descend into the position shown in Figure 3, so that it covers over the gate 8, whilst, at the same time, the double-pronged claw 18 has imparted to it a downward advancing movement thereby engaging and drawing down the film 33, as shown in Figure 3, the tail member 22 of the claw 18, through its sliding motion in the block 23 and the displacement of its pivot connection to the claw 18, effecting the rocking of said block 23 with consequent retraction of the pin 25 from its engagement in the film 33.

Further rotation of the disc 17 effects the movement of the claw 18 away from the film 23 so that said claw 18 is returned to the position shown in Figure 1. During this movement, the tail member 22 of the claw 18 by changing its angular position and sliding downwardly in the pivotal block 23, causes the block 23 to rock and bring its pin 25 into a position such that the end of said pin 25 first passes into a film perforation to retain the film during exposure and then withdraws to a position just behind but not touching the film, the spool-carrying spindle 37 at the same time being rotated through the spring band 39 to wind on the film, said spring band allowing slip as the diameter of the film spool increases.

During the above-described cycle of operations, the claw 18 is maintained at all times in an attitude such that the prongs 21 thereof are perpendicular to the film track, this being ensured by the provision of the guide pin 20 fixed on the

plate 19, which latter slides up and down in the channel guideways 10. Correct engagement with the film is thus ensured, and there is no risk of the film becoming torn.

In the rear end wall of the casing 1 and coaxial with the lens-carrying member 5 there is formed an aperture fitted with a rim 42, in front of which, and spaced therefrom, is a ring 43 upstanding from the partition 2, said rim 42 and ring 43 serving for the reception therein of an artificial lighting device indicated generally by reference numeral 44, which is used when the apparatus is required for projecting. A sliding shutter 45 mounted in a vertical guideway is provided for covering the aperture in the rear end wall of the casing when the apparatus is used as a camera.

I claim:—

In apparatus for taking and/or projecting motion pictures, the combination of film-feeding mechanism comprising a rotatable disc, an eccentrically positioned pin on said disc, a feeding claw pivotally mounted on said pin, prongs on said claw adapted to engage into the film perforations, a guide member for said feeding claw, comprising a plate slidably mounted in a guideway disposed parallel to the film track and a pin affixed to and projecting at right angles from said plate and slidably engaging the claw, a film-retention mechanism comprising a block pivotally mounted on a pin secured in a fixed part of the structure, and a film-engaging and retaining pin pivotally attached to said block, and an arm pivotally connected to the feed claw and slidably engaging the block of the retaining mechanism for oscillating said block as a result of changes in the angular disposition of the arm produced by the circular motion of the feed claw and thereby moving the retaining pin into engagement with the film when the feeding claw disengages therefrom and vice versa.

ARTHUR ALLEN ANDREWS.
